Ross C. Muzzo, Toledo, Ohio

Application February 18, 1939, Serial No. 257,207

2 Claims. (Cl. 51—176)

This invention relates to surfacing and re-surfacing, more particularly with portable power equipment.

This invention has utility when incorporated in an apparatus for treatment in smoothing and finishing surfaces as of tables, platforms, floors and the like.

Referring to the drawings:

Fig. 1 is a plan view, with parts broken away, of an embodiment of the invention in position on a bowling alley;

Fig. 2 is a view on the line II—II, Fig. 1, with parts broken away, showing in section from the rearward or receding side the apparatus in position on a bowling alley;

Fig. 3 is a view in elevation from the right of Fig. 2 with the shell or cover portions removed and the track partly broken away;

Fig. 4 is a section on the line IV—IV, Fig. 3, showing features of the transmission;

Fig. 5 is a section on the line V—V, Fig. 4, showing the yieldable holding means for the clutch control;

Fig. 6 is a detail view on an enlarged scale on the line VI—VI, Fig. 4, showing the eccentric control pin in the clutch operation;

Fig. 7 is a view of the transmission or gear set-up, with parts broken away, on the line VII—VII, Fig. 4;

Fig. 8 is a fragmentary view of the surface planer adjusting means on the line VIII—VIII, Fig. 3;

Fig. 9 is a section on the line IX—IX, Fig. 8, showing features of the cutter or planer;

Fig. 10 is a fragmentary view in side elevation of the offset cutter arrangement of the planer;

Fig. 11 is a section on the line XI—XI, Fig. 2, showing features of the drive between the surfacing rolls and adjustment as well as features of the mounting of the power or additional section on the main section;

Fig. 12 is a plan view, with parts broken away, of the additional or power section embodying the motor and fan;

Fig. 13 is a section on the line XIII—XIII, Fig. 11, showing features of the polishing or sanding roll;

Fig. 14 is an enlarged detail view on the line XIV—XIV, Fig. 13, showing the sand paper terminus anchoring device;

Fig. 15 is a section on the line XV—XV, Fig. 13, showing the adjustment or operating lock for the paper terminus fastening means;

Fig. 16 is a fragmentary view in side elevation, showing the substitutive or roller mounting as against self track propulsion for the main section or carrier;

Fig. 17 is a section on the line XVII—XVII, Fig. 2, showing features of the collector in the

main section or carrier for transit to the additional section or fan;

Fig. 18 is a section on the line XVIII—XVIII, Fig. 17, on an enlarged scale, showing the attachable tube or duct between the dust collector ways of the main section and the intake duct to the fan;

Fig. 19 is a view on the line XIX—XIX, Fig. 17, showing features of the dust collector in proximity to the planer or main cutter roll;

Fig. 20 is a detail view on an enlarged scale in plan showing the shoe at the side way or gutter of the alley in providing a mounting for the track;

Fig. 21 is a section on the line XXI—XXI, Fig. 20, showing the assembly of this cutter-carried shoe for the track, parts being broken away;

Fig. 22 is a fragmentary view of a cutter or planer roll having an angle of pitch for the cutter blades; and

Fig. 23 is a view on the line XXIII—XXIII, Fig. 22, showing the cutter blade mounting.

In carrying out the invention herein, special adaptability is to bowling alleys 1 (Figs. 1, 2) having side ways or gutters 2. In this gutter 2 (Fig. 21) may be located threaded sockets 3 flush with the bottom of the gutter 2 so as not to disturb or interfere with any ball travel in bowling. These threaded sockets 3 may receive bolts 4 in anchoring shoe 5. This shoe 5 (Figs. 2, 20, 21) carries upstanding portions 6 for pair of screws 7 to engage the under side of T-rail 8, depending leg 9 of which T-rail is definitely located between screws 10. There is thus provided a leveling and sidewise locating substantial support for the T-rails 8, 9. These T-rails 8, 9, are, as positioned by the socket screws 3, located in the troughs of the gutters or side ways 2. The rails are positioned for continuity throughout the side ways for the length of the alley or therebeyond and as therebetween for the pair of gutters spaced by the alley. This relationship therebetween is for parallelism and the sighting for the length of the alley is to determine accuracy in direction and extent of inclination. There is predetermined a master control for bringing the surface of the alley between the ways to a finish condition. The track sections 8, 9, have dowels 11 controlling alignment between such. Furthermore, upstanding therefrom are additional dowels 12 and screw holes 13. In these screw holes 13 may enter screws 14 in anchoring rack sections 15 with the track 8, which rack sections are entered by the dowel pins 12 for supplementing the anchorings by way of the screws 14. There is thus provided a pair of parallel rack-carrying tracks at the adjacent sides of the alley, which tracks may be readily placed and removed to clear the alley.

This portable apparatus includes frame 16 60

(Figs. 2, 3) connected by parallel tubes 17, 18, with second frame 19. The tube 18 (Fig. 11) provides rockable bearing for pair of sockets 20, each having set screw 21 anchoring minor arm 5 tubes 22 having weld connection with platform 23, on which is mounted by bolts 24 (Fig. 2) motor 25 as the prime mover herein. This motor 25 has shaft 26 protruding at one end to carry multi-blade fan 27 in housing 28 to create suction 10 on uptake elbow 29 and deliver particles to duct 30 therefrom, say into removable bag 31. This motor 25 at its opposite end from the fan 27 has pulleys 32 for V-belts 33. This pair of V-belts 33 from the twin pulley 32 (Figs. 3, 8) pass 15 about pulleys 34 on shaft 35, thence about pulleys 36 on planer drum 37 and back to the pulley pair 32.

The shaft 35 (Fig. 4) has jaw clutch element 38 normally thrown by helical compression spring 20 39 into mesh with complementary jaw clutch element 40 fixed with pinion 41 loose on stub shaft 42 in alignment with the shaft 35. The frame 16 provides sleeve 43 in which is stem 44 having enlarged upper portion 45, from which extends 25 radially operating arm or handle 46 (Fig. 3). There is thus provided means for turning the stem 44 on its axis so that normally locking ball 47 (Fig. 5) as thrust by compression helical spring 48 seated by screw plug 49 may be effective while this ball 47 is in seat 50 to so position the stem 44 that its offset crank terminus 51 (Figs. 4, 6) engages in collar 52 of the clutch element 38. As the arm 46 is shifted so that the ball stop 47 rides from the seat 50 into seat 35 53 (Fig. 5), the crank 51 may be effective to withdraw the clutch element 38 from engagement with the clutch element 40 and thereby disconnect this power drive from transmission effectiveness as to the pinion 41.

40 This pinion 41 (Fig. 7) is in mesh with gear 54 on shaft 55 fixed with pinion 56. This gear 54 is in constant mesh with gear 57. Mounted on shaft 58 is control arm 59 (Figs. 3, 4) carrying sleeve 60 housing helical compression spring 61 normally thrusting detent 62 into seat 63. Operation of control handle 64 to clear this detent 62 of seat 63 and bring such to seat 65 shifts the control arm 59 and with it shaft 66 carrying gear 67 from mesh relation with pinion 68 on shaft 69 45 fixed with the gear 57. This shifting of the gear 67 clear of the pinion 68 is into mesh relation with the pinion 56 and results in reverse direction higher speed rotation for this gear 67, thence effective through its pinion 70 to actuate gear 71 50 on the shaft 58. This gear 71 has fixed therewith pinion 72 in mesh with gear 73 on shaft 74. This shaft 74 has toothed portion 75 in mesh with the rack 15 on the track 8 in addition to which other rollers may engage the track to distribute the support. This shaft 74 (Fig. 2) extends from the frame 16 to the frame 19 and there has toothed 60 portion 76 in mesh with the companion rack 15 on the companion or parallel track 8.

65 The cutter roll 37 (Figs. 8, 11) has, remote from its pulley end 36, pulley 77 from which extend pair of belts 78 to pulley 79 fixed with drum 80 parallel to the cutting roll or drum 37. This drum 80 is accordingly driven in the same direction and at a less peripheral speed at all times 70 than the cutting roll 37 is operating whether or not the roll 37 be in contact with the surface. This driving of the surfacing rolls 37, 80, is at all times coincident with the driving of the propulsion means for the apparatus. However, in this 75 functioning the surfacing rolls are adjustable to

not only a desired functioning position but to inoperative position for either or both thereof. To this end, key terminus 81 (Figs. 1, 2, 11) is fixed to sprocket wheel 82 and is on shaft 83 carrying worm 84 in mesh with worm wheel 85 for adjusting stem 86 to bearing 87 for the driven end of the surfacing drum 80. This sprocket wheel 82 has sprocket chain 88 therefrom to sprocket wheel 89 (Fig. 2) on shaft 90 effective through worm wheel 91 (Fig. 3) in operating stem 92 in adjusting bearing 93 for the roll 80 remote from the bearing 87. This adjustment, say for 360° rotation of the actuator key 81 may be such as to raise or lower the surfacing drum 80 .005 of an inch and horizontal or parallel to the track as 15 well as parallel to the cutter roll.

Adjacent this key 81 is key 94 on shaft 95 (Fig. 11) extending past the drum 80 and there carrying worm 96 in mesh with worm wheel 97 for adjusting stem 98 in positioning bearing 99 of 20 the drum or cutter roll 37. This shaft 95 has thereon sprocket wheel 100 with sprocket chain 101 therefrom to sprocket wheel 102 (Fig. 3) on shaft 103 having worm 104 in mesh with worm wheel on shaft 105 to adjust bearing 106 simultaneously with the bearing 99. This means that this cutting drum 37 is adjusted in parallelism as to the surfacing roll or drum 80 as well as in parallelism with the determined placing of the track. Likewise here this adjustment for a single 30 rotation of the control key 94 may be for .005 of an inch in lifting or lowering this cutting roll planer.

These adjustable stems for the opposite ends of the planer roll have upwardly extending portion 107 (Fig. 8) upon which may rest screw stem 108 carried by extension arm 109 from the deck 23. There is thus a control for the load as on the cutting roll in this additional or auxiliary frame as carrying the motor and that this adjustment is 40 a further feature in the belt tightener control.

High speed rotation cutter roll 37 (Figs. 8, 9, 10) is shown with longitudinally extending ways or seats 110 in which screws 111 may lock cutter knives 112. These seats 110 are staggered in overlapping relation so that continuity therebetween is effective in the high speed rotation of this planer or cutting tool for the more vigorous re-surfacing or surfacing operations.

In some practice, instead of seats 110 on the drum 37, there may be continuous pitch or spiral providing seat 113 (Figs. 22, 23). This angle of pitch in experience has been up to 15°. This seat may be anchored with the drum 37 by screws 114 and have such supplemented by welding 115. Screws 116 may anchor cutting knives 117 in assembly with this seat 113. These knives 117 are of more than one dimension so that as between the successive cutting knives on a common drum 37, the break termini or ends may be staggered, thereby to avoid ridges or roughening in the cutting region or the surface under treatment.

Supplemental finishing drum or roll 80 in the instance herein shown is provided with cushioning surface 118 (Figs. 13, 14, 15) such as sponge rubber, about which may be wrapped the sheet 119 of abrasive such as sandpaper or emery cloth. The drum 80 is shown with slot 120, through which ends 121 of the sheet 119 may be drawn and assembled through slot 122 in shaft 123, protruding through the ends of the drum 80 to carry ratchet 124 which may be engaged by pawl 125 (Fig. 15) as rocked on fulcrum 126 and so held by set screw 127 having lock nut 128. The initial setting or tightening of the wrap of the sheet 75

abrasive for final surfacing or even polishing material may be as to its wrapping of the ends initially effected by a crank on keyed projection 129 of this shaft 123.

5 It is primarily contemplated that the drive for the re-surfacing action of the rolls shall be in the forward or slow speed direction only. Accordingly, there is provided material removal take-off or dust collector means at the riser side of these 10 rolls and drums or cutter which are as herein shown turning in the direction against that in which the travel is being effected. Between the frames 16, 19, extends rod 130 (Figs. 17, 19) having bracket 131 locating intake nozzles 132 having notched or serrated lower terminus 133 adjusted 15 with the roller or cutting drum in approximate contact with the surface 1 being acted upon. This nozzle 132 from its thin narrow intake enlarges in its rise upward to communicate with 20 cross duct 134 herein shown as having dual connection from the supply nozzles. Medially and therebetween this duct 134 has upstanding collar 135 into which may slip sleeve section 136 (Fig. 18) from flexible depending intake elbow 19 of the 25 multi-blade fan 27. This is accordingly a readily disconnectible passage permitting assembly in taking out as occasion may require.

In addition to this accumulation take-off device for the more harshly acting roll or drum 37, 30 there is positioned adjacent the roll 80 intake nozzle 138 also having trailing hinged serrated nozzle portion 139 similar to the trailing nozzle portion 133 from the nozzle 132. This portion is likewise serrated at its lower surface-contacting 35 or approximately contacting terminus and shown having return bend 140. From this intake nozzle the thin or slot-like portion of the nozzle is inwardly tapered and thickened in upwardly extending portion 141 communicating with the 40 cross duct 134 as a way for the finer removed portions than those from the roll 37, all to be accumulated in the collector, and from this collector into the receiver or bag 31. This disconnectible duct connection wherein the collar 45 135 receives the sleeve 136 for the flexible duct portion 137 allows entrance of this portion 136 to the holding collar 142 as abutting the flanged collar 135.

The apparatus of this disclosure may be housed 50 in detachable shell 143 (Figs. 1, 2). As occasion arises to shift the equipment, say from one set of alleys or courses to another, this shell 143 may be cleared from the assembled apparatus. The drive belts 37 are taken off the drive pulley 32. 55 Set screws 21 are released so that the arms 22 may be slipped free as the motor and fan unit is, with the deck 23, lifted and cleared as an additional or auxiliary section from the main section as carrying the surfacing devices. This 60 removal is permitted for the duct disconnection is readily effected from the collar 135. In practice, this power unit may be of weight say around three or four hundred pounds. This would leave an approximately similar weight for the main 65 section. These two sections are accordingly such that they may be readily re-located even to the extent of loading and carrying elsewhere.

In this shifting, it is to be noted that the rod 130 and parallel rod 144 (Figs. 1, 2, 11, 16, 17) 70 protrude terminally beyond the frame and may have placed on such protruding portions rollers or wheels 145 as held in place by keys 146. This positioning of the rollers 145 is such as to have the apparatus as a unit carrying not only the

additional or power section but the main section so that there may be ready shifting from alley to alley or even used for re-surfacing in progressing this mobile apparatus about a skating or dancing floor or other surface to be treated. 5

In carrying out the invention herein, this power apparatus or equipment is such that it may be operated for a once-over complete treatment of a surface as a bowling alley with such surface brought to a definite location and finish 10 independent of what may have been the condition or inaccuracies theretofore. This means that an untoward condition is not inherited but is cleared off for the side ways permit the track location for definitely controlling the position. 15 The adjustment of the surfacing means determines the depth of cut or finish to occur. This finish may be for the cutter or planer as the major surface portion removal and a sander or polisher for the final finish, and this operation 20 in the disclosure herein may be at the rate of say 3 feet a minute in the finishing direction, which on a 60 or 63 foot alley would mean that the complete finishing could be effected in not to exceed 21 minutes. The return to start on a 25 different course is power effected at one-half this length of time or 10 or 11 minutes. Of course, if there be purpose in locating the depth of portions to be taken off, there may be running of say the cutter roll 37 alone to see if it is getting 30 down to the surface desired. At such time it is only necessary to elevate the finishing drum 80 to be clear of the way in the travel of the apparatus. As this depth of cut is thus determined, the final run may be of the roll 80 alone with 35 the cutter 37 elevated clear or the cutter down for finishing cut and the roll 80 to effect the final surfacing.

The roll 80 has counterweight 147 (Fig. 11) to balance the strip or sheet tightening means. 40

What is claimed and it is desired to secure by United States Letters Patent is:

1. Apparatus for dressing the surface of bowling alleys having side ways embodying a carrier sustained from the side ways clear of the alley 45 therebetween, rollers to support the carrier, tracks for the rollers including rack means, preset fixed sockets in the ways for the tracks, surfacing means mounted by the carrier, adjusting means between the carrier and surfacing means 50 for positioning the surfacing means relatively to the alley, and a power drive for the carrier and surfacing means including toothed gears to engage with said rack means.

2. Apparatus for treating surfaces embodying 55 a carrier, a plurality of surfacing means mounted by the carrier, independent adjusting means between the carrier and respective surfacing means for positioning the surfacing means relatively to each other and the surface to be treated, a collector for surface removed material, said carrier including a main section and an additional section, said latter section providing mounting for a power drive and a fan actuated thereby, duct connections from the fan to the collector, 60 transmission connections from the drive to the surfacing means, rocking bearing means provided by the main section, arm means extending therefrom for rockably mounting the additional section on the main section, and disconnecting 65 means for the arm means as to the bearing means.

ROSS C. MUZZO.
